[57] CLAIM

The ornamental design of a hammer handle grip, as shown and described.

DESCRIPTION

FIG. 1 is a front elevational view of the hammer handle grip of my new design;

FIG. 2 is a right side view thereof;

FIG. 3 is a bottom end view thereof;

FIG. 4 is a rear elevational view thereof;

FIG. 5 is a left side view thereof; and,

FIG. 6 is a top end view thereof.

The hammer fragment illustrated by means of the broken line in FIGS. 1, 2, 4, and 5 has been shown for illustrative purposes only.

FIG. 1FIG. 2FIG. 3

FIG. 4FIG. 5FIG. 6
